CIRCUIT INTERRUPTER

Albert P. Strom, Forest Hills, Pa., assignor to
Westinghouse Electric Corporation, East Pitts-
burgh, Pa., a corporation of Pennsylvania

Application August 31, 1944, Serial No. 552,064.

8 Claims. (Cl. 200—147)

1

This invention relates to circuit interrupters in general and, more particularly, to arc-extinguishing structures therefor.

The use of a magnetic field to move or spin the arc in a circuit interrupter around some path between the open contacts has been found to be beneficial since it reduces contact burning and generally also increases the voltage or current that can be interrupted. Such a construction is shown in United States Patent 2,333,598 which was issued to me on November 2, 1943, and which was assigned to the assignee of the instant application.

In the aforesaid patent, an arc is established between cooperable ring-shaped electrodes and is rotated therearound by a radial magnetic field while being simultaneously subjected to either a radial outward or inward gas blast. However, when magnetic spinning is applied to an interrupter in which flow of the liquid or gas interrupting medium also occurs, undesirable effects are encountered under some conditions due to arc looping. In the case of tubular contacts with radial flow, the arc may be pushed along by the flow into an elongated bow so that whereas the distance between contacts may be only a fraction of an inch, the arc length may actually be many times this contact separation. Consequently, the main body of the arc is no longer perpendicular to the field, but almost parallel to it, and hence has only a very feeble force tending to maintain its spinning motion. In some cases, part of the arc may move entirely out of the main field. Uncontrolled elongation of the arc is further undesirable since it raises the arc voltage during the portion of the half cycle when current is large, and hence increases the energy available to decompose and expand the interrupting medium, and also to erode the contact surfaces.

One solution for the above problem is presented in a patent application by Winthrop M. Leeds, Serial No. 549,575, filed August 15, 1944, and assigned to the assignee of this invention. This patent application describes and claims structure employing a longitudinal flow of fluid coupled with a rotating arc to thereby prevent bowing of the arc out of the magnetic field.

My invention describes types of circuit interrupters in which negligible arc looping should occur, even when both flow and magnetic spinning are employed. This is accomplished by dividing the flow passage by a plurality of arc terminal members into a plurality of passages so narrow that heavy current arcs will not loop thereinto.

2

The general object of my invention is to provide an improved circuit interrupter in which interruption of the circuit passing therethrough is accomplished more effectively than heretofore.

Another object is to provide an improved circuit interrupter in which the cooperable electrode structure consists of a plurality of annular spaced arc terminal members between which the established arc is rotated by a magnetic field. Preferably, a fluid blast, either gaseous or liquid, is forced through the electrode structure to subject the rotating arc to a fluid blast substantially longitudinally of its length.

Further objects and advantages will readily become apparent upon a reading of the following specification taken in conjunction with the accompanying drawings, in which:

Figure 1 is a vertical sectional view of a circuit interrupter embodying my invention, taken substantially on the line I—I of Fig. 2, the parts being shown in the partially open circuit position;

Fig. 2 is a sectional view taken along the line II—II of Fig. 1;

Fig. 3 is a sectional view taken along the line III—III of Fig. 1;

Fig. 4 is a sectional view taken along the line IV—IV of Fig. 1;

Fig. 5 is a plan view of the modified type of circuit interrupter shown in Fig. 6 and taken substantially along the line V—V of Fig. 6;

Fig. 6 is a vertical sectional view of a modified type of circuit interrupter taken along the line VI—VI of Figs. 5 and 7, the parts being shown in the partially open circuit position;

Fig. 7 is a sectional view taken substantially on the line VII—VII of Fig. 6; and

Fig. 8 is a perspective view of a magnetic yoke member used in the construction of the circuit interrupter shown in Fig. 6.

Referring to the drawings, and more particularly to Fig. 1 thereof, the reference numeral 1 designates an insulating tubular casing in which is fixedly secured the stationary electrode structure or fluid exhaust electrode generally designated by the reference numeral 2. In this instance, the electrode structure 2 comprises a plurality, in this instance three, spaced conducting tubes or annular arc terminal members 3, 4 and 5 concentrically positioned within the casing 1 having fluid exhaust passages therebetween.

The conducting tubes 3, 4 and 5 are maintained in position by being inserted in recesses 6 provided in a conducting web member 7, the latter being secured to the casing 1 by a bolt 8 and nut 9. Preferably, the web member 7 and the tubes

3, 4 and 5 are composed of a non-magnetic material, such as copper or brass.

Threadedly secured at 10 to the web member 7 is a magnet core 11 composed of a suitable magnetic material, in this instance iron, and having an insulating plug 12 suitably secured at the lower end thereof to prevent a terminal end of the arc from attaching thereto.

Disposed about the casing 1 is a field coil 13 comprising a winding of copper strap more clearly shown in Fig. 3. Also, surrounding the casing 1 at the lower end thereof is a second field coil 14 having a winding of copper strap and producing a magnetic field opposed to the field produced by the field coil 13, such that a radial magnetic field is established between the stationary electrode structure 2 and the movable electrode structure or fluid entrance electrode generally designated by the reference numeral 15. In this instance, the electrode structure 15 comprises a plurality of, in this instance two, spaced conducting tubes or annular arc terminal members 16, 17 suitably secured in recesses 18 provided in a movable web member 19 having a fluid entrance passage provided therebetween. The web member 19 in this instance forms an integral part of a conducting cylinder 20 actuated by a web structure 21 also integrally formed therewith. A movable insulating operating rod 22 threadedly secured at 23 to the web structure 21 causes actuation of the same. Preferably the tubes 16, 17 and parts 19, 20 and 21 are composed of a suitable non-magnetic material, such as copper or brass.

From the foregoing description, it is apparent that the electrical circuit passing through the interrupter comprises the terminal strap 24, field coil 14, strap 25, stud 26, flexible conductor 27, conducting cylinder 20, movable electrode structure 15, cooperable stationary electrode structure 2, web member 7, bolt 8, field coil 13 to the terminal strap 28. To open the electrical circuit passing through the interrupter, the operating rod 22 is moved downwardly to cause a separation between the conducting tubes 16, 17 from the stationary conducting tubes 3, 4 and 5 to draw an arc 29. The radial magnetic field set up by the field coils 13 and 14 indicated by the dotted lines 30-31 causes a rotation of the arc 29 about the cooperable electrode structures.

Preferably, in conjunction with the rotation of the arc 29 about the opposed edges of the conducting tubes, a fluid blast, either gaseous or liquid, passes upwardly through the casing 1 and between the tubes to subject the rotating arc 29 to a fluid blast substantially longitudinally of its length. As mentioned previously, the insulating plug 12 prevents an establishment of a terminal end of the arc on the magnetic core 11. Similarly, an insulating plug 32 prevents the establishment of the other terminal end of the arc 29 to an end of the magnetic core 33 threadedly secured at 34 to the web member 19.

If desired, apertures 35 may be provided in the conducting tubes to more effectively direct the fluid blast adjacent the rotating arc 29. The rotation of the arc 29 continues until it is extinguished. It will be observed that the fluid blast is longitudinally of the arc 29 and consequently does not tend to force it to assume a bowed shape as was the case in the aforesaid Patent 2,333,598.

To effect a closure of the contact structure to reestablish the electrical circuit passing therethrough the operating rod 22 is merely moved upwardly by suitable means, not shown, to cause a reengagement between the conducting tubes.

Suitable means, not shown, may effect an initiation of the fluid blast and a stopping thereof following extinction of the arc 29.

While it is highly desirable to keep heavy current arcs as short as possible, it may be desirable to let the upper terminal of small current arcs move up between the concentric tubes 3, 4 and 5 on the outlet side of the arc region. This action is permitted by this construction because large currents tend to restrike at the lower edges of the concentric tubes 3, 4 and 5, whereas small current arcs may lengthen somewhat before re-striking. The spacing between the tubes 3, 4 and 5 may be limited to between $\frac{1}{4}$ and $\frac{1}{2}$ inch to prevent travel of heavy current arc terminals up between the electrode cylinders 3, 4 and 5. On the inlet side the spacing between the tubes 16 and 17 may be wider since there is no tendency for the arc terminal to move against the fluid flow.

The discharge area between the concentric tubes 3, 4 and 5 on the discharge side of the arc region should be sufficiently small, as compared to the inlet area between tubes 16, 17, and casing 1, so that a considerable part of the fluid pressure, especially where a gaseous fluid is employed, is maintained in the arcing region, in order to maintain high dielectric strength in the arc region.

In the embodiment of my invention shown in Figs. 5 through 8, it will be observed that I have provided an insulating tube 38 having threadedly secured at 39 adjacent its upper end an insulating ring-shaped plate 40. Screws 41 secure a conducting ring 42 to the plate 40. The stationary or outer fluid exhaust electrode structure 43 in this instance comprises a plurality of, in this instance four, spaced ring-shaped conducting plates or annular arc terminal members 37, 44, 45 and 46, secured in position by a plurality, in this instance eight, screws 47 which pass through an insulating disc 53. Washers 48 mounted on the screws 47 serve to space the plates to provide fluid exhaust passages therebetween.

Disposed above the disk 53 and below the insulating ring-shaped plate 40 are two soft iron rings 57 which serve to uniformly distribute the flux of a transverse magnetic field between the electrode structure set up by field coils generally designated by the reference numerals 58 and 59. Associated with the field coils 58, 59, being formed by two pancake coils, are a plurality, in this instance eight, magnetic yoke members generally designated by the reference numeral 60. The configuration of the yoke member 60 is more clearly shown in Fig. 8. Referring to this figure, it will be noted that the yoke member comprises an L-shaped portion 61 and a clamping portion 62 secured to the L-shaped portion 61 by a screw 63.

The several yoke members 60 also serve to hold in position the field coils 58, 59. Outside of the soft iron rings 57 are insulating ring-shaped plates 64, 65.

The movable or inner fluid entrance electrode structure 66 comprises a plurality of, in this instance two, ring-shaped conducting plate members or annular arc terminal members 67, 68 secured in position by extensions 69, in this instance forming integral portions of a conducting cylinder member 70. The extensions 69 form supporting shoulders 71 upon which rest a ring-shaped conducting plate member 68. A segmental spacer member 72 spaces the ring-shaped plate member 68 from the other ring-shaped

plate member 67 to provide a fluid entrance passage therebetween. Above the plate 67 is a second spacer 73. A screw 74 passes through the two spacer members 12, 73, through the two plate members 67, 68 and has its lower end threadedly secured at 75 to the extension 69.

A conducting operating rod 76 is threadedly secured at 77 to a web structure 78, in this instance forming an integral portion of the cylindrical member 70.

The operation of this embodiment of my invention will now be explained. In the closed circuit position, the electrical circuit passing through the interrupter comprises the terminal strap 79, conducting ring 42, ring-shaped conducting plate member 68, extensions 69, cylindrical member 70, web structure 78 to conducting operating rod 76. Thus, in the closed circuit position of the interrupter, both field coils 58 and 59 are shorted out, the ring-shaped plate 68 engaging in abutting relation the conducting ring 42.

To open the electrical circuit through the interrupter, the operating rod 76 is moved upwardly by suitable actuating means, not shown, thereby causing a separation between the ring-shaped plate 68 and the conducting ring 42. This establishes an arc, the initial terminal positions of which are at the points 83, 84. The fluid blast, passing upwardly through the cylindrical member 70 and radially outwardly between the cooperable electrode structure, carries the arc which was initially established between the points 83, 84 to a position between the lower conducting ring 68 and the ring-shaped plate 37.

Now, however, the two field coils 58, 59 are brought into series circuit. In other words the electrical circuit now passing through the interrupter comprises terminal strap 79, strap 81, lower field coil 59, strap 88, strap 89, upper field coil 58, strap 90, washer 91, screw 47, stationary electrode structure 43, arc 82, movable electrode structure 66, conducting cylinder 70 to conducting operating rod 76.

The transverse magnetic field set up between field coils 58, 59 and indicated by the dot and dash line 85, causes rotation of the arc 82 around the opposed peripheries of the ring-shaped plates 68, 69. During this rotation of the arc 82, it is simultaneously subjected to a radially outward fluid blast which passes upwardly through the cylindrical member 70 and radially outwardly between the extensions 69 and outwardly between the magnetic yoke members 60. The rotation of the arc 82 continues until it is extinguished.

To complete the electrical circuit through the interrupter, it is merely necessary to move the conducting cylindrical member 70 downwardly by the operating rod 76 until the ring-shaped plate 68 strikes the conducting ring 42 in abutting relation, thereby completing the electrical circuit through the interrupter and shorting out the field coils 58 and 59. Suitable means, not shown, may effect an initiation and a ceasing of the fluid blast. The conducting rings 44, 45, 46 and 37 on the discharge side of the arcing region should be spaced sufficiently close together so that the high current arc terminals will not readily travel down between them. While it is highly desirable to keep heavy current arcs as short as possible, it may be desirable to let the terminal ends of the small current arcs move outwardly between the ring-shaped plates 37, 44, 45 and 56 on the outlet side of the arcing region. This action is permitted by the disclosed

construction because large current arcs tend to restrike at the inner peripheries of the ring-shaped plates 37, 44, 45 and 46; whereas small current arcs may lengthen somewhat before re-striking. The proper spacing between the ring-shaped plates 37, 44, 45 and 46 should be limited to between $\frac{1}{16}$ and $\frac{1}{8}$ inch to prevent travel of heavy current arc terminals outwardly between the ring-shaped plates 37, 44, 45 and 46. On the inlet side of the arcing region, the spacing between the ring-shaped plates 67 and 68 may be wider since there is no tendency for the arc terminal to move against the fluid flow.

The discharge area between the ring-shaped conducting plates 37, 44, 45 and 46 on the discharge side of the arcing region should be sufficiently small as compared to the inlet area so that a considerable part of the fluid pressure, especially where a gaseous fluid is employed, is maintained in the arc region, in order to maintain high dielectric strength in the arc region. For low current values the proper spacing on the outlet side would be in order of $\frac{1}{16}$ inch. For high current values this spacing would be slightly more, that is, $\frac{1}{8}$ inch.

Another arrangement for creating a transverse magnetic field between the stationary electrode structure 43 and the movable electrode structure 66 would be to eliminate the field coils 58, 59 and to magnetize the magnetic yoke members 60, in effect converting the magnetic yoke members 60 into a plurality of permanent magnets. If such a construction were used, the coils 58, 59 could be eliminated together with the disclosed arrangement for shorting out said field coils. This arrangement is, however, not disclosed in the drawings.

The magnetic field is provided to give a field perpendicular to the arc 82 and hence to cause it to move rapidly around the concentric arc gap. With this construction, a very short air gap can probably be used if superimposed pressure is used to increase the dielectric strength of the gas. It is believed that about 100,000 R. M. S. restored volts per inch arc length can be interrupted with 10 atmospheres back pressure. Arc energy is thus reduced to a low value. Contact burning is negligible if the field moves the arc 82 rapidly around the contacts.

I have tested a circuit interrupter of the type shown in Fig. 1, using oil as the interrupting fluid. The performance indicated absence of arc looping since arc voltages were much lower than with the transverse fluid flow. The outside insulating tube diameter was $2\frac{1}{4}$ inches, and the contact separation was 0.5 inch. Interruptions were good at currents up to 2,000 amperes at 13.8 kv. The need for a large exit area to handle large currents in oil may be avoided by utilizing high pressure gas flow as the interrupting fluid.

From the foregoing description, it will be apparent that I have provided a circuit interrupter which produces a rotation of the arc to minimize contact burning and increase cooling and deionization; and that in conjunction with such a rotation I have employed a longitudinal fluid blast, either gaseous or liquid, to more readily effect arc extinction, but yet preventing lengthening or bowing of the arc out of the magnetic field.

Although I have shown and described specific structures, it is to be clearly understood that the same were merely for the purpose of illustration and that changes and modifications may readily be made therein by those skilled in the art without

departing from the spirit and scope of the appended claims.

I claim as my invention:

1. In a circuit interrupter of the fluid blast type, a fluid exhaust electrode including a plurality of spaced annular arc terminal members all at one potential and having a fluid exhaust passage therebetween, a fluid entrance electrode including a plurality of spaced annular arc terminal members all at one potential and having a fluid entrance passage therebetween, said annular arc terminal members of the two electrodes having their larger surfaces and the passages therebetween extending in substantially the same direction and having their edge portions facing each other at all times, and said edge portions providing an arc gap between the two electrodes during interruption of the circuit, means for establishing an arc which plays in the gap between the facing edges of the spaced annular arc terminal members, magnetic means for rotating the arc around the arc gap between the edges of the spaced annular arc terminal members of the two electrodes, and means for causing a flow of fluid which flows without major change of direction while flowing through the spaces between the annular members of the entrance electrode, longitudinally of the arc across the arc gap and through the spaces between the annular members of the exhaust electrode.

2. In a circuit interrupter of the fluid blast type, a fluid exhaust electrode including a plurality of spaced annular arc terminal members all at one potential and having a fluid exhaust passage therebetween, a fluid entrance electrode including a plurality of spaced annular arc terminal members all at one potential and having a fluid entrance passage therebetween, said annular arc terminal members of the two electrodes having their larger surfaces and the passages therebetween extending in substantially the same direction and having their edge portions facing each other at all times, and said edge portions providing an arc gap between the two electrodes during interruption of the circuit, means for establishing an arc which plays in the gap between the facing edges of the spaced annular arc terminal members, magnetic means for rotating the arc around the arc gap between the edges of the spaced annular arc terminal members of the two electrodes, a housing in which said entrance and exhaust electrodes are mounted in spaced relation to the housing to provide fluid flow passages between the outer of a plurality of said annular arc terminal members of each electrode and the housing so that fluid may flow on opposite sides of each of a plurality of said annular arc terminal members and longitudinally on opposite sides of the arc in the gap between the facing edges of the annular arc terminal members of the two electrodes, and said passages between and outside of said annular arc terminal members of both electrodes extending in the same general direction so that the fluid may flow smoothly past both electrodes and longitudinally of the arc gap therebetween without substantial change in direction.

3. In a circuit interrupter of the fluid blast type, a fluid exhaust electrode including a plurality of spaced annular arc terminal members all at one potential and having a fluid exhaust passage therebetween, a fluid entrance electrode including a plurality of spaced annular arc terminal members all at one potential and having a fluid entrance passage therebetween, said annular arc terminal members of the two electrodes having

their larger surfaces and the passages therebetween extending in substantially the same direction and having their edge portions facing each other at all times, and said edge portions providing an arc gap between the two electrodes during interruption of the circuit, means for establishing an arc which plays in the gap between the facing edges of the spaced annular arc terminal members, magnetic means for rotating the arc around the arc gap between the edges of the spaced annular arc terminal members of the two electrodes, means for causing a flow of fluid which flows without major change of direction while flowing through the spaces between the annular members of the entrance electrode, longitudinally of the arc across the arc gap and through the spaces between the annular members of the exhaust electrode, and the width of the spaces between the annular arc terminal members of the exhaust electrode being between $\frac{1}{8}$ and $\frac{1}{16}$ inch to aid in keeping the arc from being elongated by being bowed into the said spaces.

4. In a circuit interrupter of the fluid blast type, a fluid exhaust electrode including a plurality of spaced concentrically disposed conducting tubes all at one potential having one or more fluid exhaust passages provided therebetween, a fluid entrance electrode including a plurality of spaced concentrically disposed conducting tubes all at one potential having a fluid entrance passage provided therebetween, the tubes of both electrodes extending in substantially the same direction and the ends of the tubes of one electrode facing the ends of the tubes of the other electrode at all times, means for establishing an arc between the facing ends of the two electrodes, magnetic means for rotating the arc around the facing ends of the two electrodes, means for subjecting the rotating arc to a longitudinal blast of fluid which passes through the fluid entrance passage provided by the fluid entrance electrode, longitudinally adjacent the rotating arc and out through the one or more fluid exhaust passages provided by the fluid exhaust electrode, the spacing between the tubes of the fluid exhaust electrode being small to aid in keeping the terminal of high current arc from being carried by the fluid blast into the spaces between the tubes.

5. In a circuit interrupter of the fluid blast type, a fluid exhaust electrode including a plurality of spaced concentrically disposed conducting tubes having one or more fluid exhaust passages provided therebetween all at one potential, a fluid entrance electrode including a plurality of spaced concentrically disposed conducting tubes having a fluid entrance passage provided therebetween all at one potential, the tubes of both electrodes extending in substantially the same direction and have the facing ends of the tubes of the two electrodes in butt engagement when the interrupter is closed, and one of the electrodes being movable out of abutting engagement to establish an arc between the facing ends of the two electrodes during the opening operation, magnetic means for rotating the arc around the electrodes, means for subjecting the rotating arc to a longitudinal blast of fluid which passes through the fluid entrance passage provided by the fluid entrance electrode, longitudinally adjacent the rotating arc and out through the one or more fluid exhaust passages provided by the fluid exhaust electrode.

6. In a circuit interrupter of the fluid blast type, a fluid exhaust electrode including a plurality of spaced concentrically disposed conduct-

ing tubes all at one potential having one or more fluid exhaust passages provided therebetween, a fluid entrance electrode including a plurality of spaced concentrically disposed conducting tubes all at one potential having a fluid entrance passage provided therebetween, the tubes of both electrodes extending in substantially the same direction and having their adjacent ends facing each other, means for establishing an arc between the facing ends of the two electrodes, magnetic means for rotating the arc around the electrodes, means for subjecting the rotating arc to a longitudinal blast of fluid which passes through the fluid entrance passage provided by the fluid entrance electrode, longitudinally adjacent the rotating arc and out through the one or more fluid exhaust passages provided by the fluid exhaust electrode, the spacing between the tubes of the fluid exhaust electrode being between $\frac{1}{8}$ and $\frac{1}{4}$ inch.

7. In a circuit interrupter of the fluid blast type, an outer electrode including a plurality of spaced conducting flat ring-shaped plates all at one potential having one or more radial fluid transmitting passages therebetween, an inner electrode including a plurality of spaced flat annular plates all at one potential disposed inside of the outer electrode and having a radial fluid transmitting passage therebetween, means for establishing an arc between the opposed edges of the two electrodes, means for rotating the arc around the opposed peripheries of the two electrodes, and means for forcing a blast of fluid through one radial fluid transmitting passage of one electrode, longitudinally of the rotating arc and then out through one radial fluid transmitting passage of the other electrode.

8. In a circuit interrupter of the fluid blast type, an outer electrode including a plurality of spaced conducting ring-shaped plates all at one potential having one or more radial fluid transmitting passages therebetween, an inner electrode including a plurality of spaced annular plates all at one potential disposed inside of the outer electrode having a radial fluid transmitting passage therebetween, means for establishing an arc between the opposed edges of the two electrodes, means for rotating the arc around the opposed peripheries of the two electrodes, means for forcing a blast of fluid through one radial fluid transmitting passage of one electrode longitudinally of the rotating arc and then out through one radial fluid transmitting passage of the other electrode, and the spacing between the spaced plates of the said other electrode being between $\frac{1}{8}$ and $\frac{1}{4}$ inch.

ALBERT P. STROM.
